COMBINED DISPLAY AND PACKAGING TRAY FOR MEAT OR THE LIKE

Paul Joonase, Taylors, and Richard R. Perdue, Greer,
S.C., assignors to W. R. Grace & Co., Duncan, S.C.

Filed May 22, 1972, Ser. No. 255,955

Term of patent 14 years

Int. Cl. D9—03

U.S. Cl. D9—242

FIG. 2

FIG. 1 is a top plan view of a combined display and packaging tray for meat or the like, embodying our new design; and

FIG. 2 is a sectional view along line 2—2 of FIG. 1.
We claim:

The ornamental design for a combined display and packaging tray for meat or the like, substantially as shown.
